UNITED STATES PATENT OFFICE.

JAMES W. IVORY, OF PHILADELPHIA, PENNSYLVANIA.

ENVELOP-OPENER AND PAPER-KNIFE.

1,259,405.

Specification of Letters Patent. Patented Mar. 12, 1918.

Application filed October 11, 1916. Serial No. 124,966.

To all whom it may concern:

Be it known that I, JAMES W. IVORY, a subject of the King of Great Britain, residing in the city and county of Philadelphia, 5 State of Pennsylvania, have invented a new and useful Envelop-Opener and Paper-Knife, of which the following is a specification.

My invention consists of a knife for slitting open the flap of an envelop, severing the fold of a slip of a piece of paper, or slitting the uncut leaves of a book, pamphlet, magazine, etc., and for other purposes, as will be hereinafter described.

15 The invention is satisfactorily illustrated in the accompanying drawing, but the important instrumentalities thereof may be varied, and so it is to be understood that the invention is not limited to the specific details 20 shown and described.

Figures 1 and 4 represent side elevations of different forms of knives embodying my invention.

Fig. 2 represents a transverse section on line 2—2 Fig. 1.

Fig. 3 represents a transverse section on line 3—3 Fig. 1.

Figs. 5, 6 and 7 represent side elevations of other embodiments of the invention. Fig. 30 8 represents an edge view of another embodiment thereof.

Similar numerals of reference indicate corresponding parts in the figures.

Referring to the drawings:

35 1 designates the blade of the knife, 2 the cutting edge thereof, 3 the curved back thereof, 4 the handle thereof, and 5 designates a bill or segmental member on the point portion of the blade. The handle extends at an angle from the inner terminal of the blade, the upper margin of said bill 40 being comparatively on a line drawn from the upper edge of said handle.

The blades in Figs. 1 and 4 are arcuate 45 downwardly from the bills 5 of the blades to the heels of the latter where they join the handles thereof, and they may be long and deep, or short and shallow.

The edges of the bill or front end of the 50 blade especially in front and on top while being blunt or dull, are sufficiently pointed at the front, so as to readily enter the fold of an envelop, piece of paper, etc., without cutting the same, after which the bill forms

a guide for the blade in its motion during 55 the cutting operation, as will be hereinafter more fully described.

It will be noticed that the cutting edge curves downwardly and upwardly from the bill to the handle, and varying from a 60 straight edge from the front point at the lower edge of the bill to said handle, so as to present an angle to the fold to be cut or severed, and this angle may vary from a 65 straight edge shallow and short, or deep and long, making a long or short blade while the handle extends at an angle as represented in the drawing, upwardly from the inner terminal of the blade 1, so as to cause the 70 shearing action or draw cut of the cutting edge on the fold of an envelop, piece of paper, etc., as will be hereinafter again, referred to.

A depression is formed in the blade where the cutting edge of the latter joins the bill 75 5 to assist in starting promptly the cutting of the fold of the envelop, piece of paper, etc., after the inner terminal of the bill passes such fold, piece, etc. In Fig. 1, the curve is about one inch and a half, and the length of the blade about two inches, including the angle and curve between the bill and handle proper, giving about one inch and a half to the anterior part of the arcuate cutting edge, and about the same distance of arcuate edge 85 to where it joins the handle.

The angle of the anterior curve of the blade is different from the ordinary blade, inasmuch as it curves upward forward from the line of the handle, while the ordinary 90 blade is merely on a line with the handle and has no guide segment to follow in the fold of paper or envelop.

The depth of the actual cutting edge of the blade at its lowest point is less than a 95 half inch from the horizontal line between the point of the bill and the handle. The front angle of the blade runs downward from the point of the segment and has a similar thickness of blade throughout its entire cutting surface in the direction of the length of the same to the curved center and also on the upwardly extending angle terminating at a point near the horizontal handle line.

In operating the device, the handle is held at an angle say 35° or more intersecting the line of the fold of an envelop or piece of

paper. The point of the bill is then inserted under the edge of the flap or piece of paper at the fold line thereof, and the knife is moved along, when the bill guides 5 the blade on said fold line without cutting, tearing, penetrating or fracturing said line, and the cutting edge slits or severs said fold with a shearing action or draw cut causing a sharp, quick, smooth and uniform severance 10 of the fold throughout the length of the latter.

In Fig. 6, I show a blade connected with a tang provided therewith by the screw 11.

In Fig. 7, I show the handle crimped in 15 the direction of its length, the same though made of light material is vastly strengthened by the crimp. In this case the blade and handle are integral, as in Fig. 1.

The angle of the blade in comparison to 20 an ordinary blade for opening an envelop, or cutting folds are on the sides like an equilateral triangle while the direction of the handle is the same.

The angle of cutting is forward and outward at an angle of about 35° , the anterior curve of the blade following the guide segment at about this angle, but the blade being on a line with the handle, the point would be at a cross direction to the anterior angle 30 shown in Figs. 1 and 2, and hence contrary to a correct angle for cutting or slitting open an envelop.

As shown in Fig. 8, the blade tapers in 35 longitudinal direction from the guide bill or guide pilot 5 toward or to the handle, so as to gradually reduce in thickness in said direction, whereby it offers less resistance and friction to the fold of an envelop or piece of paper, etc., and so it cuts clean and easier 40 than heretofore, especially in a push stroke of the blade in the cutting or slitting operation.

In all cases, the guide bills or guide pilots

5 are substantially the same in operation and result.

Having thus described my invention what I claim as new and desire to secure by Letters Patent, is:—

1. A knife of the character stated composed of a blade having an arcuate cutting 50 edge, and a handle, the latter extending inclined upwardly from the heel of said blade, the upper margin of the point of said blade being on a line drawn from the upper edge of said upwardly inclined handle. 55

2. A knife of the character stated composed of a blade having an inturned arcuate cutting edge, a bill on its front end, and a handle, the latter extending angularly rearward of said blade, the edges of the point 60 and sides of the bill being comparatively blunt and dull, the upper margin of said bill being comparatively on a line drawn from the upper edge of said angular extending or inclined handle. 65

3. In a knife of the character stated, a blade having an arcuate cutting edge, a handle which is inclined from the rear end of said blade, and a dulled bill on the forward end of said blade, said blade having 70 therein a depression intermediate of the bill and the cutting edge of the blade. 75

4. A knife of the character stated composed of a blade having an inturned arcuate cutting margin, and a bill on its forward end, the edges of the point and sides being blunt and dull, and a handle, which latter extends at an angle from the inner terminal of said blade in the longitudinal direction of the latter, the upper edge of said bill being 80 comparatively on a line drawn from the upper edge of said inclined handle. 85

JAMES W. IVORY.
